ATTORNEY

H. A. Thomas

WITNESS:

UNITED STATES PATENT OFFICE.

NORMAN L. COLLTON, OF NEWPORT NEWS, VIRGINIA.

SCREEN FOR AUTOMOBILES.

Application filed September 4, 1926. Serial No. 133,624.

This invention relates to means for screening the openings of an automobile of the closed type, the general object of the invention being to provide means whereby the 5 screen carrying frame is slidably held in a window opening and is capable of moving in a plane parallel to the plane of movement of the window.

A further object of the invention is to 10 provide means whereby the screen will be raised by the raising of the window but can remain in raised position after the window is lowered, with means for permitting the lowering of the screen while the window is 15 in lowered position.

A further object of the invention is to provide frictional means for holding the screen in raised position.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:—

Figure 1 is a view showing the invention in use.

Figure 2 is a section on line 2—2 of Figure 1.

Figure 3 is a section on line 3—3 of Figure 1.

Figure 4 is a section on line 4—4 of Figure 1.

Figure 5 is a perspective view of one of 40 the guiding strips.

Figure 6 is a sectional view on line 6—6 of Figure 8.

Figure 7 is a sectional view through the lower part of a window.

Figure 8 is a perspective view of a screen 45 frame.

Figure 9 is a view similar to Figure 7, but showing a modification.

Figure 10 is a fragmentary perspective 50 view of a modification.

Figure 11 is a fragmentary view showing an arrangement whereby the screen is placed outside of the sash.

In these views, 1 indicates a guiding strip 55 which is of channel shape in cross section

and is provided with a hook 2 at its upper end which is formed on one side of the strip. This hook is adapted to engage an opening 3 formed in the inner member 4 of the window frame. One of these strips is placed at each side of the window opening, with its outer edge engaging an inner edge of the packing member 5 of the window glass 6. The lower end of each strip 1 extends into the opening which receives the glass when 60 said glass is lowered. If desired, I may form slotted ears 7 on each guiding member 1', the slots of which receive the screws 8 which connect the inner member 4 of the frame to the door or other part in which the 65 window is located. This modification is shown in Figure 10 and in dotted lines in Figure 3.

The screen frame 9 which carries the wire mesh 10 has its side edges engaging the 70 members 1 so that the screen is parallel with the window glass and is movable in the space between the glass and the inner part of the window frame. The screen is caused to move upwardly with the window by 75 means of the hooks 11 which are fastened to the bottom edge of the channel member 12 which carries the glass and these hooks engage the lower edge of the screen frame so that as the glass is raised, the screen is also 80 raised. The upper edge of the screen frame is provided with hooks 13 which engage the upper edge of the glass so that the screen frame is prevented from rattling when the 85 glass or window is in raised position. A pair of guiding strips 14 is arranged in the opening below the window opening for preventing the screen from swinging inwardly 90 when in lowered position, which might cause the screen to contact with the window operating means and thus prevent movement of the screen. A strap handle 15 is connected with the top of the screen frame to permit the same to be lowered. In cases where the window is of considerably greater dimensions than the window opening, I may make the hooks 11 as shown at 11' in Figure 9, so that the lower edge of the screen can project beyond the lower edge of the window 95 or glass.

The screen is frictionally held in raised position by means of the projections 16 each carried by a spring plate 17 fastened to the inner side of each strip 1 and projecting through a hole in said strip so as to engage 100

a depression 18 formed in each side of the screen frame.

From the foregoing, it will be seen that the guiding strips 1 can be easily and quickly placed in position at each side of the window opening by placing the hooks 2 in the small openings 3 made in the inner member of the window frame. When necessary or desired, strips can be supported by the screws 8 and the slotted ears 7. The window screen is slidably mounted in these strips and said screen is moved to closed position as the window is closed through means of the hooks 11. The frictional fastening means 16 and 17 will prevent the screen from moving downwardly with the window when the window is opened, but a slight pull on the handle 15 will partly lower the screen so that it can be pushed all the way down by pressing upon the upper edge thereof.

Thus I have provided simple means for screening in the openings of a vehicle, the screens being movable in the openings which receive the window glass so that the invention can be applied to a motor vehicle with but little change and at low cost.

Figure 11 shows an arrangement whereby the screen can be placed outside of the sash. In this case, the guiding strips 1" are each made slightly shorter than in the case where the screen is placed inside and each strip is provided with a horizontal extension 19 at its lower end forming rests for the hooks 13' on the screen when the screen is in lowered position. In this case, the hooks at the tops of the guiding strips would engage openings formed in the outer member 4 of the window opening.

In this form of the invention, the hooks 13' will hold the screen in lowered position, it being held in raised position by the friction means before described. When in lowered position, the strap handle would be visible so that the screen can be raised when desired. In this position of the screen, the window can be raised and lowered without moving the screen so that the windows can be washed without interference from the screens.

It is thought from the foregoing description that the advantages and novel features of my invention will be readily apparent.

I desire it to be understood that I may make changes in the construction and in the combination and arrangement of the several

parts, provided that such changes fall within the scope of the appended claims.

What I claim is:—

1. In combination with a window of a vehicle, channel shaped guiding strips having hooks at their upper ends and placed at the sides of the window opening with their hooks engaging portions of the window frame, a screen frame slidably mounted in the channel shaped strips, means connected with the movable part of the window for raising said screen frame when said movable part is raised, frictional means for holding the screen frame in raised position and a handle connected with the screen frame to permit the same to be lowered.

2. In combination with a window of a vehicle, channel shaped guiding strips having hooks at their upper ends and placed at the sides of the window opening with their hooks engaging portions of the window frame, a screen frame slidably mounted in the channel shaped strips, means connected with the movable part of the window for raising said screen frame when said movable part is raised, frictional means for holding the screen frame in raised position, a handle connected with the screen frame to permit the same to be lowered, said frictional means comprising a spring strip fastened to one of the guiding strips, said guiding strip having a hole therein and said spring strip having a projection entering the hole and engaging a part of the screen frame.

3. In combination with a window of a motor vehicle and the vertically movable sash thereof, a pair of members of channel shape in cross section arranged at the sides of the window opening and connected with the inner portion of the window frame, a screen frame slidably mounted in the guiding members, a hook on the lower edge of the sash for engaging the lower edge of the screen frame, a hoop on the upper edge of the screen frame engaged by the upper edge of the sash when the same is raised, friction means carried by the guiding members for holding the screen frame in raised position, a handle connected with the upper part of the screen frame and guiding strips in the sash receiving opening below the window opening for preventing inward movement of the screen frame.

In testimony whereof I affix my signature.
NORMAN L. COLLTON.
